UNITED STATES PATENT OFFICE.

CHARLES COUPLAND, OF SEYMOUR, CONNECTICUT.

APPARATUS FOR STEAMING CLOTH.

SPECIFICATION forming part of Letters Patent No. 350,187, dated October 5, 1886.

Application filed October 5, 1885. Serial No. 179,001. (No model.)

To all whom it may concern:

Be it known that I, CHARLES COUPLAND, of Seymour, in the county of New Haven and State of Connecticut, have invented an Improvement in Apparatus for Steaming Cloth, of which the following is a specification.

Woven cloths, and especially piled fabrics, have been subjected to the action of steam for raising the nap. In this operation considerable time is consumed in hanging the cloth in such a manner that the steam has access to all parts of it, and large and costly structures have been required for this operation. Besides this, the cloth is often injured by drops of water falling upon the same from the condensation of the steam.

The object of my present invention is to overcome the aforesaid difficulties by facilitating the hanging up of the cloth and the removal of the same, and by maintaining a sufficiently-high temperature to prevent any condensation of steam, and at the same time to increase the rapidity of the steaming operation.

In the drawings, Figure 1 is a vertical section of the apparatus complete. Fig. 2 is an inverted plan of the cloth-holder, and Fig. 3 is a plan of the base of the machine below the line *xx*.

I make use of a central standard, A, near the top of which is an inverted conical cloth-holder, B, said cloth-holder having upon its under surface ranges of small hooks, as shown in Fig. 2, said small hooks being adapted to the reception and support of the cloth by penetrating one edge thereof. These ranges of hooks are in the form of a volute or spiral, in order that one range of hooks may be out of the way of the edge of the cloth while being hooked upon the next range of hooks, and the cloth-holder can be revolved upon the vertical standard A, so that the attendant in suspending the cloth hooks the selvage at one end of the piece upon the hook that is lowest down and nearest to the center of the inverted conical cloth-holder, and he proceeds to revolve such cloth-holder and to present the edge of the cloth so that the hooks will enter near the selvage, and thereby suspend the cloth, and this operation is continued until the whole piece of cloth is suspended from the under side of the cloth-

holder in the form of an open spiral or volute. The different convolutions of the cloth, however, do not touch each other, and there is sufficient space for the steam to circulate upwardly between such convolutions of the cloth. The reverse movement allows for the cloth being pulled off as the cloth-holder is revolved after the steaming operation has been performed. This cloth-holder suspends a piece of cloth in a very small compass, and allows for the hanging up or removal of the cloth much more rapidly than in machines heretofore constructed.

It is preferable to make use of a grooved flange, c, upon the standard A for the reception of anti-friction balls c', forming a bearing that supports a similar flange, c', attached to the bottom and central part of the cloth-holder B. The standard A is tubular and provided with a cock, D, below the bottom of the apparatus, and there are openings 3 into this tubular standard at the level of the grooved flange c, so that any water of condensation that may be upon either the upper or lower surfaces of the cloth-holder may run down and escape by the tubular standard, and not drip upon the cloth.

The aforesaid cloth-holder and tubular standard may be employed with any suitable casting and steam-supplying devices. I however prefer to use a hollow base, E, through which the standard A passes, and into which a steam-pipe, F, enters to supply steam to a perforated ring, G, around the standard A. The supply of steam is regulated by a cock, F', and the steam issues from the perforations in the ring G and passes up between the folds of the cloth, and I use an annular cover, H, over the steam-ring, the same being supported by suitable legs and acting to prevent drops of water issuing with the steam from reaching the cloth that is suspended above such steam-pipe, and there is a pipe and cock, k, through which water of condensation may be drawn off. The upper edge of the base E is formed as a flange, L, upon which rests the flange M at the bottom of the inclosing-case N, this case N being sufficiently large to cover and pass freely down around the cloth-holder and cloth, and there is to be a rubber or other packing, L', between the flanges L and M, to make a tight joint.

This inclosing-case is counterpoised by a weight upon a chain or rope, P, that passes over the pulleys Q, so that the case can be easily raised or lowered. It is guided in its 5 up and down movements by the vertical rods R, that pass through and are fastened in the flange L, and the guides M and S upon the case N and jacket V slide upon these rods, and when this inclosing-case has been lowered to 10 place, it is preferably secured by keys passed through mortises 5 in the guide-rods R. This case N retains the steam while the same is acting upon the suspended cloth, and a safety-valve is preferably employed at T, to avoid 15 risk from too great pressure.

If this apparatus is used in a hot room, a steam-jacket around the inclosing-case will not be required; but usually I provide the same, as shown at v, the steam being supplied to the 20 jacket through the pipe v', and the water of condensation passing off by the pipe v'', the connections to these respective pipes being made by either flexible tubes or telescopic tubes v' v'', so as to allow for the raising and lowering 25 of the inclosing-case.

By the use of the steam-jacket v, I am able to maintain a sufficiently-high temperature in the cloth-steaming apparatus to prevent the risk of condensation; hence the cloth will not 30 be injured by drops of water, and the rapidity of the steaming operation is promoted.

I do not claim volutes with pins for receiving the cloth in stretching-machines. In these the pins, all being in the same plane, are not 35 easily accessible in hooking on or removing the cloth.

I claim as my invention—

1. A cloth-holder in the form of an inverted cone having hooks upon its under surface arranged spirally or as a volute, in combination 40 with a central support upon which the cloth—

holder can be revolved in applying or removing the cloth, and a surrounding case and steam-supply pipe, substantially as set forth.

2. The tubular standard A, having around 45 the same a flange and ball-bearings, in combination with a cloth-holder in the form of an inverted cone and hooks upon such cloth-holder arranged as a volute, there being an opening into the tubular standard for passing 50 away any water of condensation, substantially as set forth.

3. The standard A and inverted conical cloth-holder with hooks upon its under surface, in combination with a base and steam-supply 55 pipe, and an inclosing-case resting upon the base and surrounding the cloth-holder and cloth, and means for raising and lowering such inclosing-case, substantially as set forth.

4. The tubular standard A, an inverted 60 conical cloth-holder, B, and hooks upon its under surface, in combination with the hollow base F, perforated steam-supplying ring G, deflector H above the same, the movable inclosing-case N, guide-rods R, and a steam-jacket and pipes connected to the same around 65 the case N, substantially as set forth.

5. The means herein specified for suspending a piece of cloth from one edge and for allowing it to be put in place or removed rapidly, 70 consisting in a central support, a volute range of suspending-pins, and an inverted conical support for the same, so that the volute ranges as they increase in diameter are successively higher up, for the purposes set forth. 75

Signed by me this 17th day of September, A. D. 1885.

CHARLES COUPLAND.
